UNITED STATES PATENT OFFICE.

GEORGE F. MITCHELL, OF WASHINGTON, DISTRICT OF COLUMBIA.

RADIO RECEIVER ATTACHMENT FOR TELEPHONES.

Application filed October 8, 1925. Serial No. 60,345.

My invention relates broadly to radio receiving systems and more particularly to the construction of a radio receiver which may be attached to the standard telephone.

5 One of the objects of my invention is to provide a simple construction of radio receiving apparatus which may be readily attached to the standard house telephone for the reception of radio broadcast news, 10 concerts, music and entertainment.

Another object of my invention is to provide a construction of radio receiving apparatus which is readily attachable to a standard telephone and which may be readily connected in the telephone circuit without the necessity of erecting an antenna or modifying the telephone installation in any way beyond making simple connections with the telephone conductors.

20 Still another object of my invention is to provide a practical construction of radio receiver attachment for telephones which may be readily transported from place to place and secured to the telephone ready 25 for operation without interference with the normal functioning of the telephone.

A further object of my invention is to provide a radio receiving attachment for telephones which may be snapped upon the usual telephone stand and the usual telephone receiver utilized both for the reception of radio signals in addition to its usual function as a receiver for the line wire telephone communication.

35 Other and further objects of my invention will be understood from the specification hereinafter following by reference to the accompanying drawings, wherein:—

40 Figure 1 is a side elevation showing the radio receiver attachment secured to a telephone stand; Fig. 2 is a rear view showing the radio receiver attachment secured to the telephone stand; Fig. 3 is a top plan view of the radio receiver attachment secured to the telephone stand; Fig. 4 is a perspective view of the radio receiver attachment; Fig. 5 is a fragmentary view partially in cross section showing the arrangement of wiring within the telephone stand where the usual telephone receiver is employed for the reception of radio signals; Fig. 6 is a modified view of a radio receiver attachment employing an adjustable tuning inductance; Fig. 7 is a perspective view showing a telephone stand with the radio receiver attachment of my invention secured thereto; Fig. 8

is a cross-sectional view showing the arrangement of miniature electron tubes and coupling transformers of a multi-stage amplifier built into the radio receiver attachment; Fig. 9 is a fragmentary view showing a telephone stand with terminals brought out for connection to a radio receiving set; and Figs. 10, 11, 12, 13, 14 and 15 show wiring arrangements which I may provide for the apparatus of the radio receiver attachment.

Referring to the drawings in more detail, reference character 1 represents the telephone stand which includes the carrier hook 2 for supporting the telephone receiver 3. 70 A flexible connection 4 is provided between the telephone receiver 3 and the telephone stand 1 from which the conductor 5 leads to the telephone box and line. The telephone stand carries the transmitter 6. A 75 vertical longitudinally extending supporting member 7 is provided forming the housing for the radio receiving apparatus with an insulated plate 8 forming one side thereof. The supporting member 7 conforms substantially to the shape of the telephone stand 1 and has a top portion 9 at the upper extremity thereof which supports a rectifier or crystal detector. The supporting member 7 is detachably secured to the telephone stand 1 by means of the resilient devices 10 and 11 having spring arms 10^a and 10^b, and 11^a and 11^b, which grip opposite sides of the telephone stand. A contact strip 12 is provided at the upper extremity of the supporting member 7 which engages and establishes 80 electrical connection with a portion of the telephone stand 1. The rectifier comprises a cup member 14 which contains sensitive crystal 15. A standard 16 is mounted on the plate 9 permitting an arm carrying a cat whisker 17 to be moved to various positions by means of universal joint 19 under control of the adjusting knob 18. I provide a latch 20 pivoted at one side of the supporting member 7 and arranged to overlie the hook 2 in abutment with pin 21 for preventing the operation of the hook 2 when the telephone receiver 3 is used as the radio receiver 95 and is removed from the hook 2. In Fig. 10 I have illustrated a simplified arrangement 100 of the receiving circuit where the telephone headset 22 is connected across terminals AA and BB which connect respectively with the contact member 22 establishing connection with the telephone stand and the ground at 26.

In Fig. 11 I have shown a form of receiving apparatus where the telephone headset 22 is shunted by means of a condenser 23 and wherein a tuning inductance 24 with 5 adjustable contact 25 is provided as schematically illustrated in Fig. 6. I may provide an electron tube circuit at the receiver as represented in Fig. 12 where a variable tuning condenser 27 is positioned between 10 the contact member 12 and the tuning inductance 24 and the tube 28 arranged to function as a detector with grid condenser and grid leak 29 in the input circuit thereof. As represented in Fig. 13 I may provide 15 stages of amplification after the detector 15-17 with an audio frequency coupling transformer 30 arranged to impress the rectified energy upon the amplifier tube 31. Fig. 14 illustrates schematically the 20 principle of my radio receiver attachment, where the input circuit of the radio receiver apparatus is virtually connected to one side of the telephone line 32 through the inherent capacity 33 existing between 25 the telephone stand and the leads. A coupling transformer 34 may be arranged to impress the received signaling energy upon the detector circuit.

In Fig. 5 I have shown the telephone stand 1 broken away illustrating interior contacts 35, 36, 37, and 38 interiorly of the stand. Wires lead from binding posts E and F to the conductors 4 which connect with the telephone receiver 3. In order to 30 more clearly illustrate my invention I have shown the terminals AA and BB in the cross-sectional view of Fig. 5 one below the other although it will be understood that they would normally appear one behind the other. Flexible connectors 39 and 40 provided with pin connections are arranged to be passed through the insulation of the 35 flexible conductor 4 to complete an electrical circuit through the telephone receiver 3, placing the telephone receiver 3 in the output 40 circuit of the radio receiving apparatus.

Fig. 7 more clearly shows the arrangement of parts of the radio receiver attachment. The wiring arrangement when the 45 telephone receiver 3 is used in the output circuit of the radio receiver is illustrated in Fig. 15. In Fig. 8 I have shown the supporting member 7 enclosing miniature electron tubes 42 and 44 and coupling transformers 41 and 43 for increasing the amplitude of the received signaling energy to such a point that reception at any desired 50 volume is practical over the radio receiver attachment. In Fig. 9 I have shown a terminal face 49 which is formed directly upon the telephone stand 1 providing socket terminals 45 for cooperation with pin terminals 47 on the connector 46 which connects through flexible lead 48 with the output circuit 55 of the radio receiving set. In this con-

struction it is unnecessary to provide pin tap connections between terminals AA and BB when it is desired to utilize the telephone receiver 3 both as a receiver of radio signals and as a receiver of the normal line 70 wire telephone communication.

It will be understood that the radio receiver attachment of my invention may be employed on the usual telephone stand without interference by the normal operation of 75 the telephone. The attachment is compact in size and is portable so that it can be taken along by a traveler and used on any telephone. The device is practical in construction and inexpensive in manufacture on a 80 quantity production basis and it is unnecessary to supply a special headset with the device in that the usual telephone receiver of the telephone may be used if desired. When attached to telephone systems where 85 one side of the line is grounded the radio set can be connected with the grounded side of the line and an independent ground connection 26 becomes unnecessary.

While I have described my invention in 90 certain particular embodiments I desire that it be understood that modifications may be made and that I intend no limitations upon the invention other than those imposed by the scope of the appended claims. 95

What I claim and desire to secure by Letters Patent of the United States is as follows:

1. A radio receiver attachment for telephones comprising, in combination, a telephone stand, a support adapted to carry radio receiving apparatus, a contact member extending from said support, and spring arms carried by said support for engagement with opposite sides of said telephone stand 100 for securing said support with respect to said telephone stand with said contact member in operative engagement with the upper extremity of said telephone stand for establishing electrical connection therewith. 105

2. A radio receiver attachment for telephones comprising, in combination, a telephone stand, a supporting block substantially conforming to the shape of said telephone stand, said block carrying radio receiving apparatus thereon, and members extending from said block and engaging said telephone stand, at least one of said members establishing electrical connection between 115 said apparatus and said telephone stand for completing an electrical circuit through said receiving apparatus. 120

3. A radio receiver attachment for telephones comprising, in combination with a telephone stand, supporting block arranged to carry radio receiving apparatus, resilient clip members for securing said supporting block in engagement with said telephone stand, and a contact member carried by said block for directly contacting with said tele- 125 130

phone stand for establishing electrical connections between said radio receiving apparatus and said telephone stand for completing the electrical circuits through said radio receiving apparatus.

4. A radio receiver attachment for telephones comprising, in combination with a telephone stand, supporting member adapted to carry radio receiving apparatus and having terminals for the connection of a telephone headset in circuit therewith, and securing members extending from said supporting member for engagement with said telephone stand, one of said securing members establishing electrical connections with said telephone stand for completing the electrical circuit through said radio receiving apparatus.

5. A radio receiver attachment for telephones comprising, in combination with a telephone stand, a supporting member carrying radio receiving apparatus, a ground terminal on said supporting member for electrically connecting said radio receiving apparatus to ground, mounting members secured to said supporting member for engagement with said telephone stand, and a contact member carried by said supporting member for directly contacting with said stand for establishing electrical connection between said radio receiving apparatus and said telephone stand for completing the electrical circuit through said radio receiving apparatus.

6. A radio receiver attachment for telephones comprising, in combination with a telephone stand, a supporting member arranged to carry radio receiving apparatus, circuit connections for said radio receiving apparatus within said supporting member, terminals carried by said supporting member for the connection of a telephone headset with said radio receiving apparatus, a ground connection terminal carried by said supporting member for establishing a circuit from said radio receiving apparatus to ground, resilient means for securing said supporting member on said telephone stand, and a connecting member carried by said supporting member and arranged to directly engage said telephone stand and establish electrical connections between said radio receiving apparatus and said telephone stand.

7. A radio receiver attachment for telephones comprising, in combination with a telephone stand, a supporting member adapted to carry radio receiving apparatus, a crystal detector mounted on said supporting member, terminal members carried by said supporting member and connected with said radio receiving apparatus, resilient clips for securing said supporting member to said telephone stand, and a member extending from one side of said crystal detector for

engaging said telephone stand and establishing electrical connections therewith.

8. A radio receiver attachment for telephones comprising, in combination with a telephone stand having a telephone receiver and a hook carrier therefor, a supporting member adapted to carry radio receiving apparatus, means for detachably securing said supporting member to said telephone stand, terminals carried by said supporting member for establishing connection between said telephone receiver and said radio receiving apparatus, and means carried by said supporting member for preventing operation of the telephone receiver hook carrier when said telephone receiver is removed from said hook and connected with the said radio receiving apparatus.

9. A radio receiver attachment for telephones comprising, in combination with a telephone stand including a telephone receiver and a hook carrier therefor, a supporting member, means for detachably securing said supporting member to said telephone stand, radio receiving apparatus carried by said supporting member, a member connected with said radio receiving apparatus and engaging said telephone stand for establishing electrical connection therewith, output terminals for said radio receiving apparatus carried by said supporting member, means for establishing connections between said output terminals and said telephone receiver and means carried by said supporting member for preventing operation of said hook carrier when said telephone receiver is removed therefrom and connected with said output terminals.

10. A radio receiver attachment for telephones comprising, in combination with a telephone stand including a telephone receiver and a hook carrier therefor, a supporting member adapted to carry radio receiving apparatus, resilient means for detachably securing said supporting member to said telephone stand, a pair of output terminals, a ground terminal and an antenna terminal carried by said supporting member, said antenna terminal being arranged to engage with said telephone stand and establish electrical connection therewith, means for establishing connections between said telephone receiver and said output terminals, and means carried by said supporting member for preventing operation of said hook carrier when said telephone receiver is removed therefrom and connected with said radio receiving apparatus.

11. A radio receiver attachment for telephones comprising, in combination with a telephone stand including a telephone receiver and a hook carrier therefor, a supporting member, means for detachably securing said supporting member to said telephone stand, radio receiving apparatus car-

- ried by said supporting member and having output terminals with leads extending therefrom for the connection of said telephone receiver therewith, and a latch member carried by said supporting member for preventing operation of said hook carrier when said telephone receiver is removed therefrom and connected with said output terminals.
12. A radio receiver attachment for telephones comprising the combination with a telephone stand having a telephone receiver and a hook carrier therefor, of a supporting member adapted to carry radio receiving apparatus, means for detachably securing said supporting member to said telephone stand, a terminal carried by said member and adapted to be brought into electrical contact with said stand to connect the radio receiving apparatus with said stand when said
- member is secured to the stand, output terminals carried by the supporting member and in connection with the receiving apparatus, and conductors for establishing connection between the output terminals of the apparatus and the telephone receiver. 20
13. A radio receiver attachment for telephones comprising the combination of a supporting member provided with means for detachably securing said member to a telephone stand, a terminal carried by said member and adapted to be brought into electrical contact with said stand when said member is secured to said stand, and means carried by said supporting member for preventing operation of the hook switch of said telephone stand when said member is secured to said stand. 30
